(57) **CLAIM**

The ornamental design for a food extrusion die, as shown and described.

DESCRIPTION

FIG. 1 is a first top perspective view of the present invention; FIG. 2 is a second top perspective view of the present invention;

FIG. 3 is a front elevation view of the present invention with the left elevation, right elevation, and rear elevation views identical to the front elevation view;

FIG. 4 is a top plan view of the present invention; and,

FIG. 5 is a bottom plan view of the present invention. The broken lines illustrate environmental features that form no part of the claimed invention.
